JOHN B. BARTLETT, OF NEW YORK, N. Y.

Design No. 3,213, dated November 3, 1868.

DESIGN FOR A GLASS BOTTLE.

The Schedule referred to in these Letters Patent and making part of the same.

To all whom it may concern:

Be it known that I, JOHN B. BARTLETT, of the city and county of New York, State of New York, have invented a certain Design for the Sides of a Glass Bottle; and I do hereby declare that the following is a full and exact description thereof.

The accompanying drawings form a part of this specification, and the letters of reference marked thereon.

My design is in imitation of an ear of corn, maize, (*Zea mays.*)

Referring to the drawings, A is the body, and A' the neck. The neck is formed by ordinary tools, in the ordinary manner. The body is moulded in the general contour of a large ear of corn, as represented, and the interior of the mould is so formed as to im-

press on the soft glass, in the act of moulding, the impression of the several grains, arranged in rows, in exact imitation of the grains in an ear of corn.

The several rows are indicated 1, 2, 3, and the several grains are indicated, respectively, *a b c.*

I exclude the stopper from my design, that being no part of the bottle.

I claim the design for the side of a glass bottle, in imitation of an ear of corn, as herein set forth and shown.

JOHN B. BARTLETT.
